UNITED STATES PATENT OFFICE.

GEORGE D. BULMER, OF DUQUESNE, PENNSYLVANIA.

MERRY-GO-ROUND.

SPECIFICATION forming part of Letters Patent No. 703,761, dated July 1, 1902.

Application filed January 14, 1902. Serial No. 89,736. (No model.)

To all whom it may concern:

Be it known that I, GEORGE D. BULMER, a citizen of the United States of America, residing at Duquesne, in the county of Allegheny and State of Pennsylvania, have invented certain new and useful Improvements in Merry-Go-Rounds, of which the following is a specification, reference being had therein to the accompanying drawings.

10 This invention relates to certain new and useful improvements in merry-go-rounds, and has for its object the provision of novel means whereby a device of this character may be easily operated; furthermore, to provide novel 15 means that will admit the mechanism to be operated by means of a motor or by hand-power by the occupants of the merry-go-round.

Another object of the herein-described invention is to provide a novel mechanism 20 wherein the friction is reduced to a minimum, thereby assuring a free and easy rotation of the device; furthermore, to provide reversible seats at the ends of the cross-beams that may be turned in either direction and securely retained in the desired position.

The present invention further contemplates providing a mechanism of the above-described character that when reduced to a miniature will form a novel mechanical toy 30 that may be operated by automatons.

With the above and other objects in view the invention finally consists in the novel combination and arrangement of parts to be hereinafter more fully described, and specifically pointed out in the claim.

In describing the invention in detail reference is had to the accompanying drawings, forming a part of this specification, and wherein like numerals of reference indicate like 40 parts throughout the several views, in which—

Figure 1 is a perspective view of my improved merry-go-round. Fig. 2 is an enlarged vertical sectional view showing a modified 45 form of power appliance. Fig. 3 is a top plan view of the central driving-gear, showing the cog-gears meshing therein. Fig. 4 is a detail view of one of the chairs or seats and showing a platform or running-board attached. Fig. 5 is a detail view of one of the 50 bearings attached to the cross-beam shown in dotted lines and also illustrating a por-

tion of one of the operating-rods having interposed therein a knuckle-joint. Fig. 6 is a vertical sectional view of the central standard, together with the mechanism secured thereto. Fig. 7 is a detail perspective view illustrating the end of one of the cross-beams, operating-rod, and seat, showing an automaton arranged therein.

In the drawings the reference-numeral 1 represents the stationary base or circular frame, upon which is secured a circular track 2. Braces 3 are secured to the interior of the base and extend to the center thereof, on 65 the upper faces of these braces 3 and at their intersection being rigidly secured arms 4. These arms are integral with one another and carry a central boss 5, in which is arranged the central stationary shaft 6, having 70 fixed thereto a circular cog-rack 7, and at the upper end of the shaft 6 is provided a canopy 8. The above parts are all stationary. Upon the circular track 2 are placed antifriction-wheels 9, which are mounted upon 75 a circular frame 10. Upon these antifriction-wheels is mounted a turn-table 11, carrying a circular track 12 on its under face fitting in the central groove of the antifriction-wheels. The turn-table 11 carries a series of 80 cross-beams 14, which are attached thereto by means of yokes 15. These cross-beams 14 extend radially from the center, where they are secured in a cross-head 16, carrying a central bearing 17, having a ball-race 18 85 formed in its upper face, in which are placed ball-bearings 19, engaging the under face of the stationary cog-rack 7. Upon the cross-beams 14 are secured a number of bearings 20, which are suitably spaced apart and are 90 adapted to receive the operating-rods 21, having formed at their ends crank-handles 22. The said operating-rods are formed in two or more sections, being connected by knuckle-joints 23, thereby relieving the strain that would otherwise take place upon the rods if constructed of a single piece. The length of the rod would otherwise cause it to spring or bind; but to still further assure the easy rotation of the rods I provide ball-bearings 24 95 in the bearings 20. At the ends of the operating-rods 21 are fixed beveled gears 25, meshing in the cog-rack 7. The chairs or seats 26 carry foot-rests 27, and to the under side

of the seats are attached screw-threaded rods 28, which extend through the cross-beam near the end thereof, thumb-nuts 29 engaging the lower end of the screw-threaded portion of the rods and serving to securely retain the chairs or seats in the desired position and permitting the chairs to be easily reversed when desired. In case the device is reduced to a miniature or toy the seats 10 may be occupied by automatons 30 to operate the mechanism.

In the modified form of my invention, as shown in Fig. 2 of the drawings, the hand-power driving mechanism is entirely dispensed with and the central shaft converted from a stationary to revolving shaft, being mechanically connected to a motor 31 in any suitable manner. A platform or running-board 32 may also be attached to either form 15 of construction, if desired, and the same is preferably suspended by means of hangers 33, secured to the cross-beams.

The operation of my improved device is as follows: The occupants of the chairs or seats 25 by turning the crank-handles of the operating-rods will operate the gears in the circular cog-rack, thereby rotating the turn-table upon the antifriction-wheels. The latter revolving will carry with it the circular frame in which 30 they are mounted. The turn-table carrying the cross-beams travels at a rate of speed that is twice as great as that of the circular frame.

The many advantages obtained by the use 35 of my improved mechanism will be readily apparent from the foregoing description and by referring to the accompanying drawings.

It will be noted that various changes may

be made in the details of construction without departing from the general spirit of my 40 invention.

Having fully described my invention, what I claim as new, and desire to secure by Letters Patent, is—

In a merry-go-round, a base comprising two 45 circular frames, suitably spaced apart with braces secured to the upper frame extending inwardly to the center thereof and carrying integrally-formed arms with a central boss carried by the arms, a track secured upon 50 the upper of said frames, a frame carrying grooved wheels mounted on said track, a turn-table comprising a circular frame carrying a track on its under side engaging in said grooves of the wheels, a stationary shaft secured in said central boss, a series of cross-beams carrying a cross-head at their one end mounted on said shaft, yokes straddling the cross-beams and secured to the frame of the turn-table, means for operating the turn-table, 55 chairs carrying U-shaped brackets seated on the upper face of the cross-beams with screw-threaded rods carried by the chair and passing through the cross-beams, U-shaped brackets secured to the under face of the cross-beams and means on the lower ends of the rods for engagement with the lower bracket whereby the seat may be retained in its predetermined position, substantially as described. 60

In testimony whereof I affix my signature in the presence of two witnesses.

GEORGE D. BULMER.
